**VAPORIZATION OF POLYCHLOROCYCLO-
HEXANES**

Albert P. Giraitis, David D. Humphreys and Thomas A. Leeper, Baton Rouge, La., assignors to Ethyl Corporation, New York, N. Y., a corporation of Delaware

Application February 29, 1952, Serial No. 274,111

4 Claims. (Cl. 260—648)

This invention relates to the dehydrochlorination of organic chlorine compounds and more particularly to a new and improved method for the vapor phase dehydrochlorination of polychlorocyclohexanes, such as benzene hexachloride and similar compounds.

The dehydrochlorination of benzene hexachloride to produce trichlorobenzene has previously been carried out at elevated temperatures, usually in the presence of iron or ferric chloride. Other improved methods have recently been developed using novel catalysts which provide more isomer selectivity, for example, for selective formation of the valuable 1,2,4-trichlorobenzene isomer. The latter isomer is useful as an intermediate in the production of valuable higher chlorinated derivatives. It may be chlorinated, for example, to produce 1,2,4,5-tetrachlorobenzene, the latter hydrolyzed to provide 2,4,5-trichlorophenol, and this product further treated with acetic acid to obtain 2,4,5-trichlorophenoxyacetic acid, commonly known as 2,4,5-T.

The preferred methods for dehydrochlorinating benzene hexachloride are carried out in the vapor state. However, vaporization of the benzene hexachloride results in undesired coking (carbon deposition) which causes fouling of process equipment and the buildup thereon of a heat insulating surface layer. Thus, frequent interruptions in operation are necessitated to assure a satisfactory flow of reactants through the process equipment and to maintain the desired heat transfer through the vaporizer walls to effect vaporization of the benzene hexachloride. In consequence, operational costs of the vapor phase processes have been relatively high, and continuous operation of the process has been impractical.

In general, it has been found desirable to melt the benzene hexachloride, vaporize the same, and dehydrochlorinate the vapors in separate steps. While all three operations, and particularly the latter two steps, may be carried out simultaneously in the same vessel, the use of separate operations facilitates control of residence times and temperature conditions to minimize precracking and undesired coking of the benzene hexachloride. Normally, the residence time in the melt pot should be as short as possible, consistent with providing an ample supply of molten benzene hexachloride for vaporization so as to minimize precracking, and the residence time and vaporization rate should be controlled within relatively close limits to prevent both coking and precracking of the benzene hexachloride to trichlorobenzene in the vaporizer.

It is therefore an object of the present invention to provide a method for dehydrochlorinating polychlorocyclohexane compounds in which the latter compound may be vaporized and subsequently dehydrochlorinated while eliminating or at least greatly minimizing the deposition of coke on the surfaces of the process equipment.

Another object of the present invention is to provide a method of the above type characterized by providing

2

a high degree vaporization per unit volume of vaporizer space.

Another object is to provide a process which will allow the maintenance of the polychlorocyclohexane compound in a molten state for relatively long periods of time without appreciable precracking thereof.

Still another object of this invention is to provide a method of the above type for benzene hexachloride which will permit occasional starting or stopping of the process without solidification of normally solid polychlorocyclohexane compound within the reaction equipment.

Other objects and advantages of the present invention will become apparent as the description proceeds especially when considered in connection with the accompanying drawing wherein:

The figure is a schematic flow diagram of one mode of dehydrochlorinating benzene hexachloride to produce trichlorobenzene embodying the features of the present invention.

Before explaining the present invention in detail, it is to be understood that the invention is not limited in its application to the process specifically described herein, since the invention is capable of other embodiments and of being practiced or carried out in various ways. Also it is to be understood that the phraseology or terminology employed herein is for the purpose of description and not of limitation.

The process of the present invention comprises dehydrochlorinating in a vapor state a polychlorocyclohexane, such as benzene hexachloride, to produce trichlorobenzene. An essential feature of this invention by which the above objects are accomplished is the addition of a quantity of trichlorobenzene to the polychlorocyclohexane to be vaporized so as to facilitate melting and vaporization thereof, and, in consequence, to prevent precracking and coking of the polychlorocyclohexane.

As noted above, it is preferred to melt and vaporize the polychlorocyclohexane in separate vessels, prior to effecting catalytic cracking in a reaction vessel. The trichlorobenzene is preferably added directly to the polychlorocyclohexane in the melt pot, thus permitting lower temperatures therein. Since in actual operation it is normally necessary to retain a relatively large volume of the molten polychlorocyclohexane for feeding to the vaporizer, resulting in long residence periods, it is highly desirable to maintain as low a temperature in the melt pot as reasonably possible. At normal melting temperatures of benzene hexachloride, for example, with the residence times generally encountered, considerable precracking thereof is frequently experienced. At the lower temperatures permitted by the addition of trichlorobenzene, such precracking is eliminated or materially reduced.

Since the 1,2,4-trichlorobenzene isomer is most valuable at this time for upgrading purposes, it is generally desired to utilize process conditions, including temperatures and catalysts, which favor 1,2,4-trichlorobenzene formation. In such cases, it is also desired to add to the polychlorocyclohexane to be dehydrohalogenated the same trichlorobenzene isomer. In actual operation, this is accomplished by merely recycling a portion of the trichlorobenzene product of the cracking operation to the melt pot for blending with the polychlorocyclohexane feed.

The quantity of trichlorobenzene which should be added to the polychlorocyclohexane is largely dependent upon the temperature desired in the melt pot, and the temperature and degree of vaporization of the polychlorocyclohexane desired in the vaporizer. The trichlorobenzene acts as a vapor carrier for the polychlorocyclohexane in the vaporizer and, at similar temperature con-

ditions, materially increases the degree of vaporization of the polychlorocyclohexane. In normal operation, the temperature of the vaporizer is generally lowered, thus eliminating or materially reducing both precracking and coking therein, and the residence time of the material in the vaporizer. The latter is one of the major factors controlling coke formation.

In general, the concentration of trichlorobenzene in the feed solution may vary between about 5 and 70 percent by weight. Normally, it is preferred to maintain a concentration of trichlorobenzene between about 30 and 40 percent by weight of the total feed stream. The feed composition obviously controls to some extent both the temperature in the melt pot and in the vaporizer. When employing a feed consisting of $\frac{1}{3}$ trichlorobenzene and $\frac{2}{3}$ benzene hexachloride, for example, it is frequently desired to maintain a temperature of about 150° C. in the melt pot and about 300° C. in the vaporizer.

Catalysts suitable for the present process are well known and include metallic iron, ferric chloride, aluminum chloride, and similar compounds. Activated carbon has recently been found to be highly effective and is preferred in employing the present process.

The addition of trichlorobenzene to the benzene hexachloride, to be dehydrochlorinated, also permits easy and efficient starting and stopping of a continuous process without danger of solidification of the normally solid benzene hexachloride in the process equipment. A preferred method of operation comprises initially filling the entire process equipment, including the melt pot, vaporizer and reactor with the normally liquid trichlorobenzene. The benzene hexachloride or other polychlorocyclohexane is then gradually added to the melt pot as temperature conditions within the process equipment approach normal operating conditions. Conversely, when it becomes necessary to shut down the process for any reason, it is preferred to gradually replace the polychlorocyclohexane in the melt pot with trichlorobenzene so as to eliminate the possibility of solidification of the relatively high melting polychlorocyclohexanes within the process equipment.

With reference to the drawing and considering steady state conditions, benzene hexachloride is melted with trichlorobenzene in a melt pot 20, the trichlorobenzene being preferably obtained as a product recycle, and the liquid mixture is continuously fed into a knockout drum 30. This molten mixture is immediately heated and is continuously circulated from the knockout drum through the vaporizer 40 and back to the knockout drum where a controlled quantity of the benzene hexachloride-trichlorobenzene mixture vapor is flashed. The latter vapor fraction is then further heated in a superheater 50 and passed into a reactor 60, wherein the benzene hexachloride vapors are cracked to trichlorobenzene. The product therefrom, essentially pure trichlorobenzene, is then liquefied in condenser 70 and collected in a trichlorobenzene holdup drum 80. The liquid product may then be withdrawn therefrom as desired. A portion of the molten mixture in the knockout drum 30 is continuously circulated through a filter feed tank 90 and a coke filter 100 to remove traces of solid carbon particles formed during the heating operations.

More specifically the melt pot 20 is connected at its top with the hopper 10 and with the trichlorobenzene holdup drum 80 through lines 11 and 81 respectively. The melt pot 20 is also vented to atmosphere through line 23. The melted mixture is circulated from the bottom of the melt pot 20 to the top of the knockout drum 30 through lines 24 and 26 by means of pump 28. Valves 25 and 27 are provided in the lines 24 and 26, respectively.

The knockout drum 30 is connected at its bottom with the bottom of the vaporizer 40 through lines 31 and 33 and pump 32, and also with the filter feed tank 90 through line 34. The outlet or upper end of the vaporizer 40 is

connected with the upper end of the knockout drum 30 through line 41.

5 The flashed vapor fraction containing benzene hexachloride and trichlorobenzene, in feed ratio, is then passed through line 35 to the superheater 50. The latter is connected through line 51 and valve 52 to the bottom of the reactor 60. Lines 61 and 71 connect the reactor 60 to the condenser 70 and the condenser to the trichlorobenzene holdup drum 80, respectively. A valve 62 is also provided in the line 61. Withdrawal of product is accomplished through line 81 and valve 82.

The filter feed tank 90 is connected through the coke filter 100 to the melt pot 20, by means of lines 91, 93 and 101 and pump 92. Valves 94 and 95 are provided in the lines 91 and 93, respectively.

10 The melt pot 20, knockout drum 30, trichlorobenzene holdup drum 80, and filter feed tank 90 are preferably simple cylindrical drums. If desired, the melt pot may be provided with internal agitation, and the knockout drum may be provided with insulation and/or jacketed.

15 The vaporizer 40, superheater 50, reactor 60, and condenser 70 are all preferably tube bundles, i. e., series of parallel tubes. The reactor tubes generally are packed with a suitable catalyst, such as activated carbon, and a screen is normally provided at the lower inlet ends of the catalyst-filled tubes.

20 The following is an example of one preferred mode of carrying out the process of the present invention.

25 The apparatus illustrated schematically in the drawing was first filled with a solution comprising essentially trichlorobenzene. This solution was continuously circulated through the system. The melt pot and vaporizer were heated externally and benzene hexachloride was gradually added to the melt pot 20 from the hopper 10 as the system approached operating temperatures. The benzene hexachloride had the following composition in percent by weight:

Alpha isomer	77.5
Beta isomer	9.9
Gamma isomer	7.0
Epsilon isomer	1.0
Heptachlorocyclohexane	2.6
Tetrachlorocyclohexane	0.3

30 After the system attained a steady state continuous operation, the benzene hexachloride-trichlorobenzene weight feed ratio was 2:1. The benzene hexachloride was fed to the melt pot at a rate of about 10 grams per minute and the melt pot was maintained at a temperature of about 195° C. This mixture was continuously fed to the top of the knockout drum from whence the same was circulated through the vaporizer 40. The temperature in the knockout drum and vaporizer were maintained at about 285° C. Turbulent flow is maintained through the vaporizer and approximately one percent of the benzene hexachloride was flashed per pass. The composition of the liquid circulated into the vaporizer was about 90 percent benzene hexachloride and 10 per cent trichlorobenzene whereas the flashed vapor had a composition essentially the same as the feed composition—66.7 percent benzene hexachloride and 33.3 percent trichlorobenzene. The flashed vapor was passed through the superheater 50 wherein the temperature was raised to about 350° C. These superheated vapors were then passed through the reactor 60 wherein the benzene hexachloride vapors were dehydrohalogenated to form trichlorobenzene, using an activated charcoal catalyst. The trichlorobenzene product was condensed at approximately 90° C. and recovered in the trichlorobenzene holdup drum 80.

35 A portion of the liquid phase in the knockout drum was circulated through a coke filter to remove quantities of coke which formed in the vaporization and the filtrate was returned to the melt pot. A sufficient quantity was circu-

lated so as to hold the coke content of the liquid benzene hexachloride solution below about 4 weight percent.

The above run was continuously conducted for 55 hours. Thereafter the apparatus was inspected and found to be essentially free of any coke deposition.

The average product recovered in the trichlorobenzene holdup drum had the following composition in percent by weight:

	Percent
1,2,4-trichlorobenzene	79
1,2,3-trichlorobenzene	9
Pentachlorocyclohexene	3
Dichlorobenzenes and tetrachlorobenzenes	9

As is believed apparent from the foregoing, the present invention eliminates or materially reduces the problem of coke formation and accumulation of coke in the melting and vaporization of polychlorocyclohexanes, such as benzene hexachloride prior to dehydrochlorination thereof by the addition of controlled quantities of trichlorobenzene to the polychlorocyclohexane compound. The trichlorobenzene additive lowers both the melt temperature and vaporization temperature and, in addition, materially aids the vaporization rate of the polychlorocyclohexane compound. Thus, the residence time in the melt pot and particularly in the vaporizer is materially reduced, in consequence substantially eliminating or greatly minimizing coke formation and precracking of the feed material.

We claim:

1. In the process of melting and vaporizing a polychlorocyclohexane compound prior to dehydrochlorina-

tion thereof under vapor phase reaction conditions, the novel steps of liquefying said polychlorocyclohexane compound in the initial presence of above about 5 percent by weight of trichlorobenzene based on the weight of said polychlorocyclohexane, and thereafter heating said liquid mixture to a temperature of at least the boiling point of the mixture to effect vaporization of the polychlorocyclohexane and trichlorobenzene.

2. The process of claim 1 wherein said polychlorocyclohexane compound is benzene hexachloride.

3. The process of claim 1 wherein said trichlorobenzene is present in the mixture in an amount between about 30 and 40 percent by weight of the polychlorocyclohexane compound.

4. In a process for melting and vaporizing benzene hexachloride prior to the vapor phase dehydrochlorination of said benzene hexachloride to produce a preponderant amount of 1,2,4-trichlorobenzene, the novel steps of heating benzene hexachloride in the initial

presence of 1,2,4-trichlorobenzene to a temperature of at least the melting point of the mixture, said trichlorobenzene being present in an amount between about 5-70% by weight of the mixture, and thereafter heating said melted mixture to at least the boiling point thereof to effect the vaporization of benzene hexachloride and trichlorobenzene.
